P. Hinckley,

Chimney Cleaner.

No 6790 X

Patented Oct. 7. 1831.

Dec 1 1851 690X
Thomas Hinkley, of Hallowell, State of Maine.

Letters Patent.

The schedule referred to in these Letters Patent and making part of the same containing a description in the words of the said Thomas Hinkley himself of his improvement in the machine for cleaning chimneys.

To all to whom these presents shall come,

Be it known that I, Thomas Hinkley of Hallowell in the County of Kennebec and State of Maine have invented a new and useful improvement in the machine for cleaning chimneys, and that the following is a full & exact description of the construction & operation of said machine as invented or improved by me.

The machine is composed of iron or steel, and is about six feet in length, A the shaft with two eyes one at top for a cord to work the machine & one at the bottom to hang a weight from if required. B. Two arms fixed into the shaft at right angles to each other. C four arms made to act with a spring movement & to open upon the arms with adjusting screws D. when the arms are adjusted to the size of the chimney, these screws fix them in that position.

The arms work upon the foot being loosely entered with a hook into the hoop B. The arms may thus be taken off at pleasure & one, two, three, or four, may be used at a time, as the case may require. E The scraper F the brush screwed down to them. The scrapers are used alone when the brushes are removed. The scraper and brush turned together upon the short arm E, horizontally and being adjusted to the chimney are then fixed with the screw. The short arm then works in the main arm by a circular tenon or joggle, & being let loose to bring the brush at a certain angle suitable to the width of the chimney, is then fixed in its place by the adjusting screw at the end of the main arm. The front brush & scraper in the accompanying drawing is represented as adjusted to a narrow chimney. The machine being adjusted (and having small cords passing from the head of each arm thru eyes in the upper end of the shaft, to prevent the arms catching in the chimney) is worked up & down by a person at the top of the chimney having it suspended by a cord. What I claim as new and as

my own invention or discovery, in the above described machine, and for the use of which I ask an exclusive privilege, is, First, the adjusting arms with screws to regulate and fit the arms for the brushy & scrapers - Second, the action of the screws by which they press constantly against the side of the chimney. Third, the mode of adjusting the scrapers & brushes upon the arms according to the dimensions of the chimney.

Witnessed
